US0D1035472S

(12) **United States Design Patent** (10) **Patent No.:** **US D1,035,472 S**
(45) **Date of Patent:** **** Jul. 16, 2024**

(54) **SECURITY SENSOR**

(71) Applicant: **Amazon Technologies, Inc.**, Seattle, WA (US)

(72) Inventors: **Wen-Yo Lu**, Pasadena, CA (US); **Alexsandra M. Bowers**, Lakewood, OH (US); **Stephen James Grant**, New York, NY (US); **Christopher Loew**, Palo Alto, CA (US); **Vinay Sao**, Malvern, PA (US); **James Siminoff**, Pacific Palisades, CA (US); **Yen-Chi Tsai**, New Taipei (TW)

(73) Assignee: **Amazon Technologies, Inc.**, Seattle, WA (US)

(**) Term: **15 Years**

(21) Appl. No.: **29/821,890**

(22) Filed: **Jan. 4, 2022**

(51) LOC (14) Cl. **10-05**

(52) U.S. Cl.

USPC **D10/104.1**; D10/106.5

CLAIM

The ornamental design for a security sensor, as shown and described.

DESCRIPTION

FIG. 1 is a top perspective view of a security sensor;

FIG. 2 is a back perspective view thereof;

FIG. 3 is a left-side view thereof;

FIG. 4 is a right-side view thereof;

FIG. 5 is a bottom view thereof;

FIG. 6 is a top view thereof;

FIG. 7 is a front view thereof; and,

FIG. 8 is a back view thereof.

The dashed broken lines depict portions of the security sensor that form no part of the claimed design.

1 Claim, 8 Drawing Sheets
